(57) **CLAIM**

The ornamental design for a helmet having a connection mechanism and a headset attached thereto as shown and described.

DESCRIPTION

FIG. 1 is a front perspective view of a helmet having a connection mechanism and a headset attached thereto according to the present invention.

FIG. 2 is a rear perspective view of the helmet having a connection mechanism and a headset attached thereto illustrated in FIG. 1.

FIG. 3 is another front perspective view of the helmet having a connection mechanism and a headset attached thereto illustrated in FIG. 1.

FIG. 4 is another rear perspective view of the helmet having a connection mechanism and a headset attached thereto illustrated in FIG. 1.

FIG. 5 is a side elevation view of the helmet having a connection mechanism and a headset attached thereto illustrated in FIG. 1.

FIG. 6 is another side elevation view of the helmet having a connection mechanism and a headset attached thereto illustrated in FIG. 1.

FIG. 7 is a front elevation view of the helmet having a connection mechanism and a headset attached thereto illustrated in FIG. 1.

FIG. 8 is a rear elevation view of the helmet having a connection mechanism and a headset attached thereto illustrated in FIG. 1.

FIG. 9 is a top plan view of the helmet having a connection mechanism and a headset attached thereto illustrated in FIG. 1.

FIG. 10 is a bottom plan view of the helmet having a connection mechanism and a headset attached thereto illustrated in FIG. 1.

FIG. 11 is a front perspective view of the helmet having a connection mechanism and a headset attached thereto illustrated in FIG. 1 and showing a visor in a lowered position.

FIG. 12 is a side elevation view of the helmet having a connection mechanism and a headset attached thereto illustrated in FIG. 1 and showing the visor in the lowered position.

FIG. 13 is another side elevation view of the helmet having a connection mechanism and a headset attached thereto illustrated in FIG. 1 and showing the visor in the lowered position; and,

(Continued)

FIG. 14 is a front elevation view of the helmet having a connection mechanism and a headset attached thereto illustrated in FIG. 1 and showing the visor in the lowered position.

The broken lines depict elements of the helmet having a connection mechanism and a headset attached thereto that form no part of the claimed design.
